UNITED STATES PATENT OFFICE.

CHARLES FRANCIS JENKINS, OF WASHINGTON, DISTRICT OF COLUMBIA.

APPARATUS FOR PROVIDING BOXES WITH CLOSURES.

1,047,530.

Specification of Letters Patent.

Patented Dec. 17, 1912.

Application filed December 2, 1911. Serial No. 663,633.

To all whom it may concern:

Be it known that I, CHARLES FRANCIS JENKINS, citizen of the United States, residing at Washington, in the District of Columbia, have invented certain new and useful Improvements in Apparatus for Providing Boxes with Closures, of which the following is a specification, reference being had therein to the accompanying drawing.

10 The object of this invention is to provide an improved automatic machine for rapidly supplying open paper receptacles with paper closures cemented in place. For illustration the receptacles chosen are previously formed 15 short cylindrical tubes, and the apparatus is employed for closing one end of each tube by cutting a disk from a strip, flanging, and inserting it after suitable adhesive has been applied.

20 In the drawings Figure 1 is a side elevation of a machine embodying the invention. Fig. 2 is an elevation of the same machine, looking from the left of Fig. 1. Fig. 3 is an enlarged plan view of the central portion of the machine with the upper portion of the frame and some other parts removed. Fig. 4 is a vertical section showing the disk cutting and closure-inserting devices. Fig. 5 is a section on the line 5—5,

30 Fig. 4. Fig. 6 is a side elevation, partly in section, showing paste applying mechanism. Fig. 7 shows in elevation the left hand end of the apparatus seen in Fig. 6. Fig. 8 shows in like manner the opposite end of 35 the same apparatus. Fig. 9 is a section on the line 9—9, Fig. 8. Fig. 10 shows in elevation a portion of a receptacle feeding wheel and its actuating mechanism. Fig. 11 is a side elevation of a cam hereinafter

40 mentioned. Fig. 12 is a plan view of a device for winding the scrap or remnant of the disk strip. Fig. 13 is a fragmentary elevation illustrating the discharge of the receptacles from the wheel which carries them.

45 Fig. 14 is an end view of a scrap drum seen also in Fig. 12. Fig. 15 is an elevation of devices. Fig. 16 is a plan view of the devices in Fig. 15. Fig. 17 is a detail elevation of parts of the apparatus of Figs. 50 15 and 16.

In these figures, A represents the supporting frame of the machine, B a receptacle-carrying wheel, and C a power pulley, mounted on a shaft C' for actuating all the

moving parts of the machine. The wheel 55 B is mounted upon a shaft B' directly below the shaft C' and is provided with a series of circumferential radial pockets B² each of which is open on one side and also at its peripheral end. This wheel is rotated step 60 by step by means of the power shaft C' (Figs. 1 and 2), spiral gears C², C³, an oblique shaft C⁴, gears C⁵, C⁶, shaft C⁷, crank-plate C⁸, and a stud C⁹ which at each revolution of the disk enters one of a series of open 65 recesses B³ in a ring B⁴ fixed on the lateral faces of the wheel B, the parts being so proportioned that each movement of the wheel corresponds precisely to the angular distance between the axes of any two consecutive pockets of the wheel, and during the time while the wheel is out of engagement, the wheel is held immovable by a mutilated disk C¹⁰, Fig. 10, this portion of the driving device being a form of the well-known "Geneva movement."

The receptacle bodies D are fed into the pockets of the wheel by a chute D', Fig. 2, down which they roll by gravity to enter the ascending pockets as they reach in succession the plane of the wheel's horizontal diameter, and as they move upward with the wheel, they are prevented from leaving the pockets by a fixed plate D², Fig. 2. Each body after it begins its ascent with the wheel 80 has the interior of its outer end provided with adhesive during a period of rest, by mechanism seen in Figs. 1, 6, 7, 8, where E is a paste receptacle from which a wheel E' transfers adhesive to a rotary brush E² 85 which is at proper times moved bodily in a direction perpendicular to its plane into and out of the mouths of receptacles carried in the pockets B² and each held temporarily at rest in position to receive the brush. These 90 devices are driven from the shaft C' by gears F (Fig. 2), shafts F', F², having universal couplings, and gears F³, F⁴, on the shaft F². The gear F³ drives a gear F⁵ on the shaft F⁶ of the paste wheel E', while the gear F⁴, through a pinion F⁰, actuates the longitudinally sliding shaft F⁷ of the brush E². The shaft F² bears at its outer end a disk F⁸ having on its lateral face a cam projection F⁹. A spring F¹⁰ on the shaft F⁷ constantly presses the rounded outer end of the shaft against the cam disk, the form of which is such that the shaft is pushed longi-

itudinally at the proper time forcing the rotating circular brush into the waiting receptacle held in proper alinement by the wheel B. In advancing from the position in dotted lines in Fig. 6, the brush passes through an aperture F¹¹ in a thin plate F¹² parallel to the brush and in close proximity to the mouth of the waiting receptacle, and as this aperture is of materially less diameter than the brush, the peripheral flexible portion of the latter is retarded until the body of the brush is well within the receptacle when the continued advance frees the brush from the plate. When thus freed, the brush instantly assumes its normal plane form and comes into contact with the interior of the receptacle. The plate thus performs the double office of removing surplus paste from the brush and preventing the advancing brush from applying adhesive to the end face of the receptacle wall, the latter result being of very great importance. As soon as the rotating brush has rubbed its glue or paste into the interior surface of the receptacle, the cam allows the spring to restore the brush to initial position, and it is to be noted that the brush now carries little paste and that in moving outward there is little tendency to leave paste upon the end of the receptacle. The plate is preferably removably held by the paste receptacle so that it may be readily removed and cleansed, and it is so placed that paste dripping therefrom falls back into the receptacle. After receiving its adhesive, each receptacle advances step by step until it reaches vertical position at the top of the wheel where it is supplied with a cup-like closure by devices to be described.

40 The closures are formed from a paper strip G from a roll G', Fig. 1, this strip being fed forward by rollers G² actuated from the power shaft by a pawl J connected with ordinary devices on the power shaft by a rod J' and engaging a ratchet J² on the shaft J³ of one feed roller. As the strip leaves the feed rollers, it passes between plane plates G³, G⁴, Figs. 3, 4, and thence over a fixed die plate G⁵, where its margins are still held in grooves G⁶. Here a disk X is cut from the strip, while it is at rest, by the descent of a die G⁷ carried by a long bar G⁸ hinged at G⁹ and having its free end raised and depressed at proper times by a rod G¹⁰ provided at its upper end with a roller G¹¹ engaging a cam G¹² on the power shaft C', Figs. 2 and 11. Immediately after the cutting of the disk a reciprocating plunger H, concentric with the die but of materially less diameter, is forced down, by devices without novelty, forming the disk into cup-shape and forcing it into the waiting receptacle. On the retraction of the plunger, the wheel B brings another receptacle to place, and 60 the operation just described is repeated. In

a rapidly running machine the working parts must be guarded from the "scrap" or unused portions of the strip. This is done by providing a reel or drum I, Fig. 1, upon which the scrap is wound, the drum being driven by an elastic belt I', from the power shaft, which permits slipping as the roll of scrap increases. The drum is free at its outer end so that the material may be slipped off from time to time and thrown aside, and to facilitate attaching and detaching the strip, the drum is provided with an open slot I², Figs. 12 and 14. Tension upon the strip is adjusted by means of a spring I³ and a thumb-screw I⁴ regulating the pressure of the spring upon the barb of the belt pulley I⁵. As a further protection, needed if the scrap strip breaks, I provide below the strip a shallow trough I⁶ extending from the die plate nearly to the scrap drum. 85

It may sometimes happen that by some chance an empty pocket arrives at the top of the wheel, and in such case it is desirable to avoid cutting and forming a closure and depositing it in the unoccupied pocket. Devices are, therefore, provided for automatically arresting the feeding of the closure strip, in such cases, and in this case such devices hold the feed pawl J out of engagement at the proper time. For lifting the pawl and holding it temporarily in raised position, I mount on the pawl-carrying arm J⁴, and just below the pawl, a rocking block J⁵ having an arm J⁶ which normally rests on a sleeve J⁷ sliding on the feed roller shaft and having a segmental peripheral flange J⁸ alongside the vertical plane of the arm J⁶. The sleeve is connected by a link J⁹ to a lever J¹⁰ centrally pivoted at J¹¹ to the frame and having at its opposite end a roller J¹² which a spring J¹³ urges toward the lower end portion of receptacles D when at rest in the wheel pocket which will at the next advance of the wheel be brought beneath the cutting and inserting devices. The flange J⁸ is normally at a slight distance from the plane of the arm J⁶, but when the roller J¹² meets no receptacles in a particular pocket, the spring swings the lever J¹⁰ so far as to carry the flange under the arm, and when, an instant later, the pawl-carrying arm J⁴ swings upward to feed the paper strip, the rounded end of the arm J⁶ rides along the abrupt terminal face J¹⁴, Fig. 17 of the flange J⁸, rocking the block J⁵, and lifting the feed-pawl J from the ratchet wheel J², and then travels along the periphery of the flange J⁸ until the arm J⁴ begins its return movement. One strip feeding step is thus omitted, and the cutter and plunger at their 115 next succeeding movements find no stock beneath them. After the roller J¹² has swung inward as described, it is pushed outward by the portion 4 of the wheel B at the next advance of the latter, and the flange J⁸ 130

being thus withdrawn from the path of the arm J^6 , feeding goes on in the normal manner.

As clearly appears in Fig. 2, the pockets 5 B^2 are so formed that when the receptacles D are descending after receiving their closures, they tend to roll out of the pockets, and as soon as they pass the plate D^2 , they roll out of the pockets into an inclined dis- 10 charge chute K , Figs. 1 and 2.

What I claim is:

1. The combination with a vertical wheel having a series of peripheral, outwardly and laterally open pockets for receptacle bodies, 15 of means for delivering such a body side- wise to each pocket upon the ascending side of the wheel as it rotates, automatic means for rotating the wheel by steps equal to the distance between the axes of successive pock- 20 ets, to bring each to rest at a predetermined

point, and a die and plunger arranged to form and insert a closure in each body while thus at rest.

2. In apparatus of the class described, the combination with a receptacle for adhesive, 25 of a rotary shaft bearing a disk extending into the receptacle, a second shaft bearing a rotary disk brush normally in contact with the disk, a cam shaft, gearing connecting the cam shaft with the disk and the brush 30 shafts, and a cam mounted upon the cam shaft and adapted to move the brush shaft longitudinally at intervals.

In testimony whereof I affix my signature in presence of two witnesses.

CHARLES FRANCIS JENKINS.
